United States Patent

Des. 239,819
Patented May 11, 1976

239,819

TIMER

Manuel Goy, 1215 S. Cloverdale Ave.,
Los Angeles, Calif. 90019

Filed Sept. 25, 1974, Ser. No. 509,248

Term of patent 14 years

Int. Cl. D10—03

U.S. Cl. D10—40

FIG. 1

FIG. 2

FIG. 5

FIG. 3

FIG. 4

FIG. 1 is a right front perspective view of a timer showing my new design;

FIG. 2 is a top plan view thereof;

FIG. 3 is a front elevational view thereof, the rear being a mirror image thereof;

FIG. 4 is a bottom plan view thereof; and

FIG. 5 is a right side elevational view thereof, the left side of the casing being a mirror image thereto.

I claim:

The ornamental design for a timer, as shown.
